UNITED STATES PATENT OFFICE.

HARRY JONES, OF SUFFERN, NEW YORK, ASSIGNOR TO THE AMERICAN BRAKE SHOE & FOUNDRY COMPANY, OF WILMINGTON, DELAWARE, A CORPORATION OF DELAWARE.

BRAKE-SHOE.

1,218,668.

Specification of Letters Patent. Patented Mar. 13, 1917.

Application filed December 28, 1916. Serial No. 139,254.

To all whom it may concern:

Be it known that I, HARRY JONES, a citizen of the United States, and a resident of Suffern, in the county of Rockland and 5 State of New York, have made and invented certain new and useful Improvements in Brake-Shoes, of which the following is a specification.

My invention relates to brake shoes, and 10 particularly to that class or type which are formed with hard metal inserts incorporated in the body of the shoe, presenting a composite wearing face.

The presence of the hard metal inserts 15 lengthens the wearing life of the shoe, and also provides for the desired amount of dressing action upon the wheel tire. In order to hold these hard metal inserts in place as the body of the shoe is being worn 20 away, it has heretofore been customary to cast or form the hard metal insert upon an openwork reinforcing member, and subsequently place the two in the shoe cavity of a mold and form or cast the body of the shoe 25 therearound. This construction results in a costly and expensive shoe and involves considerable labor and difficulties in its manufacture. A somewhat different method, heretofore used, for securing the inserts in 30 place, was by forming the same as a number of separate blocks and providing them with projections extending toward the wearing face of the shoe. These projections extended through the openings or mesh in an open- 35 work reinforcing member, tending to hold the separate inserts in place and subsequently aiding in anchoring the inserts in the body of the shoe. In actual practice, however, the inserts in some instances would 40 shift one with respect to the other, preventing the proper flow of cast metal between the adjacent inserts. A further disadvantage to this construction, was that after the body of the shoe and reinforcing member, 45 which latter was adjacent the wearing face of the shoe, had been worn away, the inserts would become dislodged and drop from the shoe.

It is therefore an object of the present 50 invention to form a brake shoe wherein the inserts are provided with rearwardly enlarging projections extending toward the back of the shoe, and also projections ex-

tending toward the wearing face thereof. The rearwardly extending projections receive the strands of a reinforcing member therebetween, and are rigidly anchored thereto by the cast metal of the body of the shoe which is formed therearound. The inserts are accordingly securely held and anchored in the body of the shoe, and so maintained as the shoe becomes worn away in service.

A further object is to provide a brake shoe in which the spacing of the inserts is independent of the openings or mesh of the reinforcing members, so that the inserts are positively held in their proper spaced relation as the cast metal of the body of the shoe is formed therearound, whereby a uniform 70 amount of cast metal extends to each side of the hard metal inserts, aiding in the securing and anchorage of the inserts and providing for the proper wear of the shoe. To this end, the reinforcing members are provided with spaced pockets in which the inserts are positioned, the formation of the pockets being such that an unobstructed 75 passage and space is provided for the flow of the molten metal above and below the inserts and reinforcing members.

Other objects and advantages will appear as the description proceeds, wherein it is to be understood that changes in the precise embodiment of the invention may be made 85 within the scope of what is claimed without departing from the spirit thereof.

The preferred embodiment of my invention is illustrated in the accompanying drawings, wherein:

Figure 1 is a top plan view of my improved brake shoe, portions of the body being broken away, disclosing the internal arrangement of inserts and openwork reinforcing and retaining members;

Fig. 2 is a view in vertical section taken on the line 2—2 of Fig. 1;

Fig. 3 is a view in side elevation, and partially in section, of the foregoing;

Fig. 4 is a detail view in side elevation, 100 of several of the hard metal inserts and the accompanying portions of modified openwork reinforcing and retaining members; and

Fig. 5 is a detail view in perspective of 105 one of the hard metal inserts.

Referring specifically to the several views, for the purposes of illustration, I have shown a driver shoe consisting of the body 10, back 11 and flange 12. Located within the body of the shoe, are the hard metal inserts 13, each of which is provided with the rearwardly extending projections 14 and the outwardly extending projections 15. The inserts, with their projections 14 and 15, are beveled or tapered downwardly, and toward the wearing face 16 of the shoe body. This general bevel or taper aids in anchoring and locking the inserts in place and holds them from outward displacement as the body of the shoe is worn away.

The inner or rearwardly extending projections 14 are sharply beveled or tapered toward their extremities, defining downwardly enlarging or dove-tailed openings 17 between the adjacent projections upon the inner face of the insert. An openwork metal reinforcing member 18 is provided and is positioned with the strands thereof contained within the dove-tailed openings of the several inserts, being so assembled prior to the casting of the body of the shoe therearound. The cast metal of the body of the shoe extends within the openings or spaces 17 between adjacent projections 14, and anchors each and every insert to the reinforcing member and prevents them from becoming detached from the shoe as the body thereof and the greater portion of the inserts are worn away in service. In order to further strengthen the body of the shoe and to maintain the inserts in spaced position prior to the forming of the cast metal of the body of the shoe therearound, the lower or outer openwork metal reinforcing member 19 is provided, and receives the outer projections 15 of the inserts therethrough.

In order to prevent the inserts from shifting or moving about as the body of the shoe is being cast, I have provided the form of construction illustrated in Fig. 4, wherein the openwork metal reinforcing members 20 and 21 are provided at spaced intervals with confronting depressions or flutes 22, between which the hard metal inserts 24 are seated. The inwardly and outwardly extending projections 25 and 26 extend through the openings in the reinforcing members and are anchored thereto at the time of casting the body of the shoe therearound. The confronting depressions or flutes 22 form channels and passageways for the molten metal, insuring a flawless casting.

What I claim is:—

1. A brake shoe consisting of a cast metal body, an insert incorporated therein and provided with projections extending inwardly away from the wearing face of the shoe, and an openwork metal reinforcing

member with the strands thereof extending between the said projections and anchored thereto by the cast metal of the body of the shoe.

2. A brake shoe consisting of a cast metal body, an insert incorporated therein and provided with projections extending inwardly away from the wearing face of the shoe, said projections defining dove-tailed openings therebetween, and a reinforcing member of openwork metal extending throughout the body of said shoe, with the strands thereof extending through said dove-tailed openings and anchored to said insert.

3. A brake shoe consisting of a cast metal body, an openwork metal reinforcing member adjacent the back thereof, and a hard metal insert incorporated in the body of said shoe and provided with projections extending inwardly away from the wearing face of said shoe, said projections enlarging toward their outer extremities and receiving the strands of the reinforcing member therebetween and anchored thereto.

4. A brake shoe consisting of a cast metal body, a plurality of hard metal inserts incorporated in said body and provided with projections extending inwardly away from the wearing face of the shoe, said projections enlarging toward their free extremities, a reinforcing member of openwork ductile metal extending throughout the body of said shoe and receiving the said projections between the strands thereof to which the said projections are anchored.

5. A brake shoe consisting of a cast metal body, a hard metal insert incorporated therein and provided with projections extending toward the wearing face of said shoe and with projections extending away from the wearing face of said shoe, and spaced reinforcing members of openwork metal incorporated in the body of said shoe, receiving the projections of said inserts between the strands thereof, the cast metal of the body of the shoe anchoring the strands of the reinforcing members to the projections of the said insert.

6. A brake shoe consisting of a cast metal body, an insert incorporated therein and provided with inwardly and outwardly extending projections, said insert and projections tapered or beveled toward the wearing face of the shoe, spaced reinforcing members of openwork ductile metal receiving said insert therebetween, with the projections thereof extending between the strands of the reinforcing members, the cast metal of the body of the shoe anchoring the strands of the reinforcing members to the projections of the said insert.

7. A brake shoe consisting of a plurality of spaced inserts, spaced openwork reinforcing members receiving said inserts therebetween, said reinforcing members provided
